UNITED STATES PATENT OFFICE.

GENNARO DRAMIS, OF BROOKLYN, NEW YORK.

FOLDING BOX.

1,155,899.

Specification of Letters Patent.

Patented Oct. 5, 1915.

Application filed August 20, 1914. Serial No. 857,730.

To all whom it may concern:

Be it known that I, GENNARO DRAMIS, a subject of the King of Italy, residing at Brooklyn, in the county of Kings and State of New York, have invented certain new and useful Improvements in Folding Boxes; and I do hereby declare the following to be a full, clear, and exact description of the invention, such as will enable others skilled in the art to which it appertains to make and use the same.

This invention relates to folding boxes, preferably to be made of paper and provided with simple, reliable and efficient means for locking the sides with the ends or for locking a cover upon the box, said box being cut from a flat blank without material waste and the locking tongues and slots for receiving the same being on the coincident radial line.

Another object of the invention is to provide locking means for the sides and ends of paper boxes, said locking means being of simple construction and being easy to engage and reliable and not liable to become detached when engaged.

The foregoing and other objects may be attained by means of the construction illustrated in the accompanying drawing, in which—

Figure 1 is a plan view of a portion of a box blank and showing the locking means for one side and one end of the box. Fig. 2 is a view looking from the inside of a box 85 toward one end during the process of uniting the sides and ends of the box by the locking tongues, and Fig. 3 is a view looking at the inner side of the ends of the box with the tongues engaged in their respective slots, 40 and the side of the box being shown in section.

Referring to the drawing, the numeral 1 designates a bottom of a box, and 2 is one end portion of the box, and 3 is one side of 45 the box.

The numerals 4 and 5 designate parallel horizontal slots in the end 2 of the box and 6 is a vertical branch of the slot 4.

The numeral 7 designates the extended 50 portion of the side 3 on which the locking tongues are formed. The locking tongue 8 is designed to engage the slots 4 and 6, and the tongue 9 which is formed on a coincident radius from the slot 5 is adapted to 55 engage the said slot. The tongue 9 is provided with a curved edge 10 on the outer side

and a reversely curved edge 12 upon the inner side. The radius *a*—*b* is struck from the center 11 and extends from the outer edge of the slot 4 to the end of the tongue 8. A radius *c*—*d* extends from the opposite end of the slot 4 to the base of the tongue 8. The radius *e*—*f* extends from the outer portion of the slot 5 to the top and terminal portion of the tongue 9, while the radius *g*—*h* extends from the opposite side of the slot 5 to the base line 12 of the tongue 9, and terminates at the point 19, and said curved line 12 leads from the corner point 20 to the point 19. The tongue 8 is provided with a plain edge 13 which terminates at the outer corner 18. The point of entrance 17 of the tongue 8 is slightly cut away in Fig. 1, said tongue having a plain lower line 15 formed by the inclined line 16 which is formed by cutting away a triangular piece at this point. When the side 3 is folded up, the corner 20 is inserted in the slot 5, and when the tongue is entirely inserted as shown in Fig. 2, the point 17 of the tongue 8 is in position to be 80 inserted in the slot 4, and when said tongue 8 is fully inserted, the side and end of the box is firmly locked in position and cannot become accidentally disconnected.

A box made in accordance with this invention can be shipped flat and can be quickly folded into box form without bending and creasing the material forming the tongues and slots, while the box is made practically without waste and the locking 90 tongues can be readily inserted by merely folding the box on the scored lines thus bringing the tongues in proper coincidence with the slots 4 and 5.

Various changes may be made in the details of construction without departing from the spirit and scope of the invention as defined in the claims.

What is claimed is:—

1. A folding box comprising a bottom side 100 and end walls, said end walls provided with superposed slits, each upper slit having a downwardly extending slit formed therewith and communicating with the inner end thereof, the end walls and side walls provided with locking tongues, said locking tongues being formed by cutting away portions of the side walls forming an upper and lower tongue, the lower tongue being adapted to engage the lower slot thereby limiting 105 the downward movement or inward movement of the side walls at the same time alin-

2
ing the upper tongue with the upper slot
thereby by inserting the upper tongue into
the upper slot, the box is pushed outward
and the cut-away portion of the upper
5 tongue limits the outward movement of the
same and holds the box in position.

2. A folding box including side, bottom
and end walls, said end walls having super-
posed transverse slits therein, upper slit
10 having a downwardly extending slit com-
municating therewith at its inner end, said
side walls having locking tongues formed
thereon, locking tongues being so formed
that they are positioned one above the other,
15 the lower tongue projecting outwardly from
the side thereof, the upper tongue extend-
ing vertically from the lower tongue having

a rearwardly extending curved portion cut-
away forming a V-shaped slot, the lower
tongue adapted to engage the lower slit on 20
the inward movement of the side limiting
the inward movement thereof, the upper
tongue engaging the rear downwardly ex-
tending slit by inserting the upper tongue
through the upper slit and pulling the side 25
outward, whereby the box will be held in an
assembled position.

In testimony whereof I affix my signature
in presence of two witnesses.

GENNARO DRAMIS.
